UNITED STATES PATENT OFFICE.

JAMES STEELE MACKENZIE, OF NORTH BEND, OHIO.

DESIGN FOR A HEATER.

SPECIFICATION forming part of Design No. 30,143, dated February 7, 1899.

Application filed January 14, 1899. Serial No. 702,188. Term of patent 14 years.

To all whom it may concern:

Be it known that I, JAMES STEELE MACKENZIE, of North Bend, in the county of Hamilton and State of Ohio, have invented and
5 produced a new and original Design for a Heater, of which the following is a specification, reference being had to the accompanying drawings, forming a part thereof.

Figure 1 is a perspective view of a heater
o embodying my design, and Fig. 2 is an edge elevation thereof.

The design in its entirety presents the appearance of a body *a*, with its upper edge *b* in circular form and its lower edge *c* in elliptical form. The lower or elliptical portion of
5 the heater-body presents two openings *d*, surrounded by flaring flanges or funnels, and

the upper portion presents circular figures *e*, said figures *e* and openings *d* being connected by tubular figures *f*, extending lengthwise 2c through the body *a*.

The leading feature of the design consists in the body presenting the circular top edge and the elliptical bottom edge, with the tubular figures running lengthwise through the 25 body.

I claim—

The design for a heater, herein shown and described.

JAMES STEELE MACKENZIE.
